UNITED STATES PATENT OFFICE.

THOMAS M. HOPKINS, OF DENVER, COLORADO.

STOVEPIPE.

1,111,384.

Specification of Letters Patent. Patented Sept. 22, 1914.

Application filed July 17, 1914. Serial No. 851,568.

To all whom it may concern:

Be it known that I, THOMAS M. HOPKINS, a citizen of the United States, residing at Denver, in the county of Denver and State 5 of Colorado, have invented new and useful Improvements in Stovepipes, of which the following is a specification.

This invention relates to portable stove pipes and consists in certain improvements 10 in stove pipes comprising a plurality of sections, adapted to be collapsed or telescoped one within the other.

More especially the invention relates to a portable stove pipe adapted for use in connection with tent stoves and the like.

One of the improvements consists in providing one of the sections with a jacket, so that the pipe may be extended through a tent-roof without danger of setting fire to 20 the same.

Another improvement consists in means for holding the jacketed section in proper relation to the tent, said means also serving to hold the sections together when collapsed.

With the above and other objects in view 25 the invention consists in general of the details of construction and combination of parts hereinafter fully described and illustrated in the accompanying drawings, in 30 which,

Figure 1 is an outline view showing a portion of a tent with the device applied thereto. Fig. 2 is a side elevation of the pipe in extended condition. Fig. 3 is a detail view 35 of a section of the jacketed joint. Fig. 4 is a view similar to Fig. 2 but with the parts collapsed. Fig. 5 is a view similar to Fig. 2 showing a modification of the device. Fig. 6 is a view similar to Fig. 4 showing the 40 modification of Fig. 5 collapsed.

In Fig. 1 is shown a tent roof 10, a stove 11 and a tent pole 12. On this tent pole is fixed a cross arm or arms 13 for the attachment of the collapsible pipe indicated in 45 general at α . These arms are not essential to the use of my invention, as the tent pole may be provided with chains or with means for attaching the stove pipe chains thereto.

Although the pipe may consist of any desired number of joints, there will always be provided a section 14 which is surrounded by a jacket 15, the latter being held in spaced 50 relation to the section and secured thereto by rivets 16. In the form shown in Figs. 55 2 and 4, this jacket is slightly longer than the section 14 and secured within the lower

end of the jacket is a ring 17. Slidably mounted within this ring is a pipe section 18 provided on its upper end with an exterior ring 19, the outer surface of which is spaced 60 from the inner surface of the section 14. 20 is an upper pipe section, which is provided around its lower end with a bead 21 bearing against the inner surface of the section 14, so that these sections 14 and 20 are held frictionally in adjusted position. The section 14 may have its upper edge bent inward, as at 22, so as to hold the section 20 from entire withdrawal, if desired. From inspection of Fig. 4 it will be seen that, when the 70 pipe is collapsed, the section 20 moves between the ring 19 and the section 14. At the upper end of the section 20 is a bracing ring 23 and extending diametrically across this bracing ring is a handle rod 24. 75

At the lower end of the section 18 there is provided an interior stop and brace ring 25 arranged for engagement by an exterior stop and brace ring 26 formed on the lower section 27. Naturally, additional sections like 80 27 may be used.

In the bottom edge of the jacket 15, there are provided oppositely disposed notches 28, and above each of these recesses is an eye 29 whereto is connected a chain 30 carrying on 85 its end a snap hook 31, adapted to engage a suitable eye on the bar 13, or be hooked onto links on the tent pole, when the pipe is extended. Moreover, when the sections are 90 collapsed, these two chains may be connected, the chains passing across the bottom of the section 14, so as to hold the collapsed pipe in that condition.

The form shown in Figs. 5 and 6 is similar to that shown in Figs. 2 and 4 but, the 95 lower section 27 is reduced at its upper end or provided with a shoulder 33, on which the ring 25 of the section 18 is supported, and section 14 has internal brackets 32, by which it, in turn, is supported on section 18. If 100 desired the shoulder 33 may be omitted and section 18 be also provided with supporting brackets 32, or both may be used, as shown in Fig. 5, and the top section may also have brackets 32 or be held by the friction of the 105 bead 21, so that the pipe is supported from the bottom, like an ordinary stove-pipe. In this form, the sections must, of course, be taken apart by drawing them out of each other downwardly and are then nested by 110 placing them in each other from the top. The chains 30 in this case, merely serve to

steady the pipe when extended out and to hold the sections together when collapsed.

Minor changes may of course be made from the exact form illustrated without departing from the essential features of the invention, as expressed in the following claims:

1. A collapsible stove-pipe for use in tents and the like, comprising a plurality of telescoping sections, one of which is provided with a double wall forming a heat-insulating jacket, said section being provided with means to secure it to the tent-pole or other member adjacent the roof of the structure through which the pipe passes.

2. A collapsible stove-pipe for use in tents and the like, comprising a plurality of telescoping sections, one of which is provided with a double wall forming a heat-insulating jacket, said section being provided with means to secure it to the tent-pole or other member adjacent the roof of the structure through which the pipe passes, said means also serving to hold the sections together in collapsed condition.

3. A collapsible stove-pipe for use in tents and the like, comprising a plurality of telescoping sections, one of which is provided with a double wall forming a heat-insulating jacket, said section being provided with means to secure it to the tent-pole or other member adjacent the roof of the structure through which the pipe passes, and each section having means to support it on the next adjacent section when the pipe is extended.

4. A collapsible stove-pipe for use in

tents and the like, comprising a plurality of telescoping sections, one of which is provided with a double wall forming a heat-insulating jacket, said section being provided with means to secure it to the tent-pole or other member adjacent the roof of the structure through which the pipe passes, the sections below said jacketed section being provided with means whereby they are suspended from said section and from each other, and the section above said jacketed section being provided with means to hold it frictionally in any position in said jacketed section.

5. A collapsible stove-pipe for use in tents and the like, comprising a plurality of telescoping sections, one of which is provided with a double wall forming a heat-insulating jacket, said section being provided with means to secure it to the tent-pole or other member adjacent the roof of the structure through which the pipe passes, the sections below said jacketed section being provided with means whereby they are suspended from said section and from each other, and the section above said jacketed section being provided with means to hold it frictionally in any position in said jacketed section, and also with a cross-bar at its top whereby the sections can be pulled apart.

In testimony whereof I have hereunto set my hand in presence of two subscribing witnesses.

THOMAS M. HOPKINS.
